UNITED STATES PATENT OFFICE

2,456,007

INDEX HEAD

Newman M. Marsilius, Trumbull, Conn.

Application August 24, 1945, Serial No. 612,509

1 Claim. (Cl. 90—57)

1

This invention relates to new and useful improvements in indexing devices and has particular relation to an index head adapted for more or less general use.

An object of the invention is to provide an index head including means wherein through the instrumentality of a single lever, as a hand lever, the index head may be unlocked, indexed and locked in its new position.

Other objects and advantages of the invention will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawing:

Fig. 1 is a top plan view of an index head, made in accordance with the invention;

Fig. 2 is an elevational view of such head, the view being taken as looking from the lower side of Fig. 1;

Fig. 3 is a horizontal sectional view taken as along the plane of the line 3—3 of Fig. 4; and

Fig. 4 is a vertical central sectional view taken as along the plane of the line 4—4 of Fig. 3.

Referring in detail to the drawing, the index head of the invention includes a base or mounting portion generally designated 10 and a head or movable portion generally designated 11. Base 10 is shown as comprising a casting including an outer annular wall 12 from a pair of opposite sides of which project bifurcated ears 13 adapted to receive clamping bolts as is well understood in the art. Additionally, the base may be provided with keys 14 adapted to be received in ways on the bed of various machines as, for example, milling machines.

Base 10 is essentially a single casting and in addition to the outer wall 12 includes an inner hub-like portion 15 receiving a depending tubular extension or post 16 formed as part of the head 11 which latter also includes a top plate 17 having bearing on the upper edge of the wall 12. Centrally of the plate 17 is a raised portion 18 shown as having a work holder 19 secured thereon as by screws or the like 20.

As the description proceeds it will become evident that the form of the work holder 19 is not an essential feature of the invention and that any desired work holder may be used. However, when the chuck type holder is used, as shown, a

2

screw 21 mounted in a bushing 22 in the hollow post 16 may be adjusted vertically to limit the extent to which the work is inserted into the open work holder. Screw 21 is adjustable by means of a nut 23 bearing against the upper side of bushing 22 and accessible through an opening 24 provided in the upstanding portion 18 of the head 11.

In a depending annular portion 25 the head 11 is provided with a series of hardened and ground bushings 26 adapted to selectively receive a longitudinally movable locking bolt 27 mounted in a sleeve or barrel 28. This sleeve or barrel is positioned in a portion of the outer vertical wall 12 of the base 10 but in a horizontal plane corresponding with that of the bushings 26. Depending from the bolt 27 is a pin 29 rigid with the bolt and constantly engaged by coil spring 30. This spring is normally urging the bolt to a locking position and returns it to such position on release of the bolt after it has been forced from locking position.

Fixed on the lower end of the post 16, as by screws 31 and dowels 32, is a ratchet wheel 33. Turnable about the post 16 as a center is a hand lever 34 the inner portion of which comprises a ring 35 encircling the post. A screw or other pivot means 36 secures one end of a pawl 37 against the underside of the lever 34 adjacent to the post 16 and a spring, as, for example, leaf spring 38, normally urges the free end of the pawl into engagement with the ratchet wheel 33. This spring is shown as fixed to the lever 34 by screws 39. A nut 40 adapted to be locked in place by screws 41 is threaded against the outer side of the lower portion of the post 16 and bears against the underside of the hub portion 15 of the base 10 to prevent relative vertical movement of the base and head.

Fixed on the lever 34 is a camming device 42. This device comprises an arcuate shaped piece having a rise 43 and then a fixed radius outer wall portion 44 to which such rise leads. In all positions of the lever 34 the cam 42 is located at the inner side of the pin 29 depending from the lock bolt 27.

Lever 34 may be turned about the lower end of the post 16 as a pivot and to enable such movement of the lever the base 10 is provided with an opening 45 through one side. Additionally, the base is provided with a rather large arcuate opening or socket 46 permitting of movement of the cam 42. In one edge portion of its wall 12 the base 10 is provided with a series of tapped openings 47 adapted to receive screws 48 used in

securing a stop block 49 in place. Obviously, through means of the screws in the tapped holes, this block may be secured in various positions.

In its forward end the block carries an adjustable screw 50 located in the path of movement of the lever 34. With this arrangement a rough adjustment of the block 49 may be made and then micrometer corrections provided by adjustment of the screw 50. In addition to the above, the lever 34 carries an adjustable screw 51 adapted to engage a portion 52 of the vertical wall of base 10. The wall portion provided with the tapped openings 47 is located slightly above the path of movement of lever 34 and in order to locate the screw 50 in such path of movement the block 49 is provided with a depending lug 54 (see particularly Figs. 2 and 4) carrying said screw.

When using the indexing head of the invention the work is secured in the holder 19 or in any other suitable holder and where a number of pieces are to be treated the screw 21 may be adjusted so that the work is simply dropped into the holder and then the holder closed onto the work. To index the work, lever 34 is moved in a clockwise direction and during such movement merely turns about post 16 as a center and at the same time the pawl 37 merely rides over the teeth of ratchet wheel 33.

As the lever 34 is given initial movement in a clockwise direction, the rise 43 of the cam 42 is carried against the pin 29, which is rigid with the locking bolt 27, and forces such pin radially outwardly. This results in the locking bolt being moved out of any of the bushings 26 with which the bolt happens to be engaged. As movement of the lever continues surface 44 of the cam is being moved against pin 29 so that the locking bolt is maintained in retracted position against the tendency of the spring 30.

When the lever has been moved to the desired extent in a clockwise direction its direction of movement is reversed. On this reverse movement the tooth of pawl 37 engages a tooth of the ratchet wheel 33 so that the lever 34 is latched to the post 16 and return movement or counter clockwise movement of the lever results in counter clockwise movement of the head 11.

At the end of the return movement stop screw 51 engages the wall portion 52 and at the same time surface 44 of the cam 42 has moved from under the pin 29 and as the rise 43 of the cam moves from under the pin the spring 30 is moving the locking bolt 27 into one of the hardened and ground bushings 26. Thus at the end of the return stroke of lever 34 head 11 has been indexed and is locked in its new position. Where a number of similar pieces are to be similarly indexed the stop block 49 is properly located so that clockwise movement of the lever 34 is positively limited to one, two, three or more of the teeth of ratchet wheel 33 so that the same movement will be imparted to each piece of work without any necessity for the operator counting the clicks as the pawl 37 moves over the teeth of the ratchet wheel.

From the above it will be seen that with the device of the invention the operator need manipulate but one lever to unlock the index head, impart the indexing movement and relock the index head. Therefore the device may be operated with

one hand while the operator has the other hand free to control a machine or any part of a machine in connection with which the present index head may be used. While the lever is against wall 52, that is, while the lever is in its normal position, the base and head are locked together.

With the adjustable stop means provided the stroke of the lever 34 and thus the extent of indexing movement imparted to head 11 may be fixed so that there is no occasion for the operator bearing in mind the precise extent to which he moves the lever 34. With the stops properly located he simply moves the lever to engage the stop 51 and then back to engage the stop screw 50 with the wall portion 52 and knows that the lever has been given the movement required for the proper indexing of the work in hand.

Having thus set forth the nature of my invention, what I claim is:

In an indexing device, a base including an inner hub-like portion and an outer annular wall-like portion extending beyond each end of said hub-like portion, a head including a central post passing through said hub-like portion of the base and a top plate having bearing on an outer end of said annular wall, an annular portion on the inner side of said plate and located at the inner side of said annular wall, said annular portion having a series of sockets therein, a locking bolt movable radially through said annular wall, a spring normally urging said locking bolt toward one of said sockets to lock the base and head together on entrance of the bolt into a socket, a ratchet wheel within said base and rigid with the inner end of said post, a lever movable about an inner portion of said post as a pivot, a pawl carried by said lever within said head and adapted to ride over the teeth of the ratchet wheel on movement of the lever from normal position and to engage a tooth of the wheel and impart turning movement to the head as the lever is moved to normal position, an elongated longitudinally curved cam within said base and rigid at one of its ends with an intermediate portion of said lever, said cam adapted to shift said locking bolt to released position and maintain it there while the lever is moved from normal position and said pawl is riding over the teeth of said ratchet wheel and during return movement of the lever while said pawl is engaged with a tooth of the ratchet wheel and said head is being turned on said base, and said cam adapted to release said locking bolt for movement into one of said sockets when the lever is returned to normal position.
